UNITED STATES PATENT OFFICE

WILLIAM B. HALL, OF CHICAGO, ILLINOIS, ASSIGNOR TO UNION RAILWAY EQUIPMENT COMPANY, OF CHICAGO, ILLINOIS, A CORPORATION OF ILLINOIS

WIRE BASKET BUNKER FOR REFRIGERATOR CARS

Application filed September 24, 1928. Serial No. 307,915.

This invention relates to improvements in wire basket bunkers for refrigerator cars.

In the construction of refrigerator cars it is a common practice at the present time to construct the ice bunkers of mesh wire of relatively heavy gauge to provide what is known as a basket bunker for the reception of the ice. These bunkers occupy space at each end of the refrigerator car, from which they are walled off by the provision of a bulkhead which is of a size to afford space above and below the bulkhead for the circulation of air.

In charging the basket bunkers with ice, particularly where salt is employed to lower the melting point, it frequently happens that the ice and salt become caked in such a way as to impede the free circulation of air through the ice in the bunker, which is essential in order to disseminate the cooling effect of the ice in the bunkers throughout the storage space in the interior of the car. In view of the fact that the maintenance of the air circulation is entirely dependent upon gravity, and due to the tendency of the cold air to fall to the floor and displace the warm air in the interior of the car, it is highly important that the circulation be maintained, and that the surface exposure of the ice be increased as much as possible within limits, in order that the air may be cooled more rapidly and an adequate circulation maintained.

The object of the present invention is to meet these conditions by the provision of fo-
35 raminous flues preferably constructed of wire mesh, which may be located singly, or preferably in groups of three, within each bunker, and so arranged as to exclude the ice from the interior of the flue or flues, so that the flues will at all times afford unobstructed passageways for the downflow of the cold air, and will also have the effect of increasing the surface exposure of the ice to the degree required to insure an adequate cooling effect.

40 The present invention is designed primarily for installation in cars having ice bunkers of the present standard construction, into which the flues may be introduced without rebuilding the present structure, although it is equally adapted for use in new installations.

Further objects and details will appear from a description of the invention, in conjunction with the drawings, wherein,—

Figure 1 is a cross sectional view of the end of a refrigerator car through the bunker, and showing the flues of the present invention arranged in a group of three; 55

Fig. 2 is a sectional view, taken on line 2—2 of Figure 1;

Fig. 3 is a horizontal sectional view of the invention corresponding substantially to the line 3—3 of Figure 1; 60

Fig. 4 is a top view of one of the side flues of the group illustrated in Figure 1; and

Fig. 5 is an enlarged view of the bottom 65 frame of one of the flues corresponding to the line 5—5 of Figure 1.

The flues of the present invention are applied to a bunker located in a car having side walls 10, an end wall 11, and a floor 12. 70 The bunker space is separated from the interior of the car by the provision of a bulkhead 13, which is spaced in the usual manner from the floor and ceiling of the car to afford passages for the circulation of air; the bulkhead being attached to vertical posts 130 75 arranged at intervals in a well-known manner. Vertical supporting posts 140 are also provided at intervals along the end wall and are utilized as supports in a manner herein- 80 after referred to.

The floor of the bunker space is afforded by a plurality of slat sections 14, which as shown are arranged in groups having their ends supported upon bars 15 of inverted 85 T formation. The groups of slat sections are connected by means of tie bolts 16 and spacer blocks 17 and are suitably supported in the bunker by means well known in the art. It is not deemed necessary to further 90 describe these details, which are of standard construction and are not special to the present construction.

The basket bunker is provided with a front wall 18 of wire mesh formation, and a rear 95 wall 19, and side walls 20 constructed of the same material, which affords a mesh receptacle for the retention of the ice.

The flues of the present invention are preferably arranged in a group of three, com- 100

prising a middle flue 21 of the full height of the car at the peak of the ceiling, and two side flues 22 each of lower height. In general, the construction of the middle flue and side flues is the same, with one exception ⁵ presently to be noted, so that in the main the description of one will suffice for all.

Each of the flues is constructed of wire mesh to afford side walls 23 and end walls ¹⁰ 24. As shown, the construction is rectangular, although the flues might be cylindrical or other configuration in cross section.

The mesh walls of the flues at the lower ends embrace a metallic frame comprising side walls 25 and end walls 26. The side and end walls of the frame are flanged, the flanges ¹⁵ 27 being bent outwardly to afford a base for attachment to the slats composing the floor of the bunker space. As shown, the center flue occupies a space between an adjacent pair of inverted T beams, and in this instance attachment is made by the provision of angle ²⁰ clips 28 which are riveted to and depend from the flanges of the bottom frame with their edges in closely adjacent relation to the inverted T beams, and also in closely abutting relation to the contiguous faces of the wooden slats, so that the angle clips 28 serve to position the base of the middle flue and prevent ²⁵ displacement thereof, without the necessity of providing positive means for attachment, although such means might be readily provided if occasion should require.

The side flues are secured in a similar manner, but in the installation illustrated each side flue occupies a space immediately above one of the T beams, and in this instance the angle clips 280 are located in position to embrace the opposite sides of the T beam, and to abut closely against the contiguous ⁴⁰ faces of the wooden slats, so that displacement is prevented.

The lower frames just described have secured to the corners thereof four upright posts 29 constituting corner posts for the flue, and in the case of the center flue these posts are of a length to extend to the top of the car, where they are secured to an upper frame 30 similar in all respects to the lower frame just described, which upper frame is provided with flanges 31 which are secured to removable blocks 32 held in place by angle brackets 33.

In the case of the side flues, the corner posts terminate below the top and are connected to an upper frame 34 which is similar to the frame previously described, with the exception that the flanges 35, instead of being turned outwardly, are turned inwardly, as shown in Fig. 4. These inwardly turned flanges lie in closely adjacent relation to a bridge bar 36 of channel formation, the ends of which are secured to ears 37 and 38 on brackets which are fastened to the appropriate front and rear posts 140 and 130 of the

bunker. The upper ends of the side flues are secured to the bridge bars by the provision of dowels 39 and locking pins 40, which afford means for easily securing the parts in position.

The arrangement is one which permits the flues to be readily inserted into place in wire basket bunkers, or other bunkers of standard construction, and by positively securing the upper ends of the respective flues against displacement, it will be unnecessary to provide positive attaching means for the lower ends, which will be held against displacement by being fitted into place in the slatted floor in the manner described.

Although a group arrangement of three flues has been described, it is obvious that a single center flue, or two side flues, might be advantageously employed, depending in each instance upon the amount of interior surface exposure of the ice it is desired to provide for.

Although, as shown, wire screening is employed it is obvious that other forms of foraminous construction might be employed without departing from the spirit of the invention.

I claim:

1. In combination with an ice bunker provided with a slatted floor, a vertical flue supported upon the slatted floor and having a foraminous wall, and means extending below the lower end of the flue and interfitting with the slatted floor to prevent displacement of the lower end of the flue.

2. A flue for use in ice bunkers, consisting of upper and lower end frames, vertically disposed posts connecting the end frames, and a foraminous wall inclosing the flue between the end frames.

3. A flue for use in ice bunkers, consisting of upper and lower end frames, vertically disposed posts connecting the end frames, a foraminous wall inclosing the flue between the end frames, means carried by the lower frame and adapted to interlock the lower end of the flue to the floor of the associated structure, and means for positively securing the upper end of the flue to the associated structure.

4. In a refrigerator car, in combination with an ice bunker having a slatted floor, a flue comprising a lower frame, an upper frame, vertical connecting bars, and a wall of wire mesh, members depending from the lower frame to afford an interfitting connection with the slatted floor of the bunker, and means associated with the upper frame for positively securing the upper end of the flue against lateral displacement.

5. In a refrigerator car, the combination with an ice bunker provided with a slatted floor, a group of three flues, the center flue extending to the ceiling of the car and the two side flues terminating below the ceiling,

each flue comprising an upper frame, a lower frame, vertical connecting posts, and a surrounding wall of wire mesh, each of the flues having secured to its lower frame depending

- 5 means adapted to interfit with the slatted floor of the bunker, the upper frame of the middle flue being positively secured to the ceiling of the bunker, and each of the side flues having a bridge bar positively connected
- 10 with the upper frame and having its ends secured to the walls of the bunker space.

- 6. In combination with an ice bunker provided with a slatted floor, a vertical flue supported upon the slatted floor and having a
- 15 foraminous wall located inwardly from and in spaced relation to the bunker wall, and means extending laterally from the flue to the adjacent bunker wall for positively securing the upper end of the flue against lateral displacement.

- 7. In combination with an ice bunker provided with a slatted floor, a vertical flue supported upon the slatted floor and having a foraminous wall located inwardly from and
- 25 in spaced relation to the bunker wall, means extending laterally from the flue to the adjacent bunker wall for positively securing the upper end of the flue against lateral displacement, and means extending below the lower
- 30 end of the flue and interfitting with the slatted floor to prevent displacement of the lower end of the flue.

In witness that I claim the foregoing I have hereunto subscribed my name this 20th

35 day of Sept., 1928.

WILLIAM B. HALL.
